CLAIM

The ornamental design for a cigarette caddy, as shown and described.

DESCRIPTION

FIG. 1 is a perspective view of a cigarette caddy, with the lid closed, showing my new design;

FIG. 2 is a perspective view thereof, showing the lid open;

FIG. 3 is a bottom plan view thereof;

FIG. 4 is a front elevational view thereof;

FIG. 5 is a left side elevational view, with the right side being a mirror image thereof;

FIG. 6 is a top plan view thereof; and,

FIG. 7 is a rear elevational view thereof.

The broken line showing of indicia in FIG. 1, and of indicia and a cigarette lighter in FIG. 2 are for illustrative purposes only, and form no part of the claimed design.
